UNITED STATES PATENT OFFICE.

HUGH W. COLLENDER, OF NEW YORK, N. Y.

POOL-RACK.

SPECIFICATION forming part of Letters Patent No. 296,136, dated April 1, 1884.

Application filed February 13, 1884. (No model.)

To all whom it may concern:

Be it known that I, HUGH W. COLLENDER, of New York city, in the county of New York, and State of New York, have invented certain new and useful Improvements in Pool-Racks; and I do hereby declare that the following is a full, clear, and exact description thereof, reference being had to the accompanying drawings, making part of this specification.

10 My invention relates to certain new and useful improvements in that class or type of pool-ball racks in which the contrivance is adapted to automatically discharge the contents of all the contained balls, when required, 15 into any suitable receptacle or tray in which the game keeper or marker carries the collected balls to the pool-table for replacement, and to that species of said class of pool-racks in which this end is accomplished by the rolling 20 of the balls from one shelf down onto the next below, and thence so on down from the lowermost shelf into the tray or receptacle.

Previous to my invention pool-racks of this species have been devised in which, however, 25 in order to effect the discharge thus of the balls from one shelf to the next below and so on down through the medium of connecting passage-ways from one shelf to another arranged at the sides of the rack, it has been necessary to have all the shelves pivoted so as to 30 tip endwise to acquire the necessary obliquity to set the balls rolling and to bring the end of the shelves into communication with the lateral passage-ways and to provide the apparatus with a more or less complex mechanism 35 for effecting and controlling the tipping of the shelves and their replacement in a horizontal position for reuse, &c.

I propose by my invention to provide for 40 use an automatically-discharging pool-rack in which, while the discharge of the balls shall be effected by their rolling from one shelf to the next below and so on down, the construction shall be exceedingly simple, economic of 45 manufacture, efficient in operation, and not at all liable to get out of order; and to these main ends and objects my invention consists, essentially, in the combination, with a suitable frame provided with vertical passage-ways at 50 each side, of a set of shelves having the ball-supporting surfaces inclined alternately in

opposite directions and adapted to be moved up and down bodily, so as to bring the lowermost end of each shelf into proper communication with the lateral passage-ways, so 55 as to permit the balls to roll down over the series of inclined surfaces, the combination and arrangement of the parts being such that when the set of shelves is in its lowermost position the balls cannot escape from any of the 60 shelves into the lateral passage-ways or communications extending from each shelf to the next one below it, all as will be hereinafter more fully explained.

To enable those skilled in the art to make 65 and use my invention, I will now proceed to describe the construction and operation of my improved pool-rack, referring by letters to the accompanying drawings, which form part of this specification, and in which I have 70 illustrated my invention as carried out in that form which is the best now known to me and in which I have so far successfully practiced it.

In the drawings, Figure 1 is a front view; Fig. 2, a vertical section at the line *xx* of Fig. 75 1; Fig. 3, a horizontal section at the line *yy* of Fig. 1, and Fig. 4 a vertical cross-section taken in a plane represented by the line *zz* at Fig. 3.

In the several figures the same parts will be 80 found designated by the same letters of reference, and while at Figs. 1 and 2 the set of shelves is illustrated in its lowermost or normal position, in Fig. 4 I have represented the shelves as raised up to their highermost position and that in which the balls on any or all of the shelves will roll down over the series of shelf-surfaces and discharge themselves at the bottom of the rack.

The main frame or frame-work of the contrivance is composed, as clearly shown, of a back board, A, a base board or bottom, B, a top or cap, C, and two hollow side portions or pilasters, D D, each of which has openings or perforations at its inner side communicating 90 with the spaces between the shelves of the ball-rack. The rack of movable shelves is composed, as shown, of a series of shelf-like boards or supports, E, connected together at their two front corners by vertical strips or bars *a*, and 95 at their back edges, near their ends, by vertical bars or strips *b*, so that all the shelves E

100

must move together. Preferably the contrivance is provided with a sort of eccentric button or lifter, *c*, arranged as shown, and provided with a T-shaped handle, *d*, by which the operator can conveniently raise them and let them fall.

E are two stops, arranged, preferably, as shown, the function of which is to stop the ascent of the set of shelves, when the latter may 10 be lifted at just the proper elevation to bring the shelf-surfaces into proper relationship with the apertures or openings communicating with the hollow pilasters *D*, in a manner and for a purpose to be presently explained.

15 As will be clearly seen, each one of the shelves *E* has its top surface dished out at *e*, the depression or dishing being greatest at one end and least at the other, so that in longitudinal section (as seen at Fig. 4) the surface 20 on which the balls rest in each shelf is gradually inclined downwardly from one end of the shelf to the other, and the arrangement of these inclined surfaces in the series of shelves *E* is such (as will be seen at Fig. 4) that the 25 balls will tend to roll along on or settle toward one end of the shelves successively in opposite directions. The set or gang of shelves thus constructed and framed together is held in place within the frame-work, preferably, 30 by means of the overlapping moldings or fillets *G*, arranged at either side of the contrivance.

By reference now to Fig. 2, it will be seen 35 that the apertures or openings in the left-hand pilaster *D* come alternately above a shelf having the lowermost portion of its ball-supporting surface adjacent to one of said openings and a shelf having its highermost ball-supporting surface adjacent to one of said openings; and by reference to Fig. 4 it will be seen 40 that a sort of inclined or chute-like roadway, *h*, which is preferably padded or cloth covered, extends in a sloping direction from the outermost portion of the passage-way in the pilaster, 45 at a point about level with the bottom of the uppermost ball-opening, downwardly in an inclined or curved direction to the lowermost edge of the next aperture or opening below, and that by this means a ball which may pass into 50 the uppermost aperture can fall or descend only to and must pass out of the pilaster again at the next opening below. In this manner a ball or balls passing, for instance, from the second shelf into the topmost aperture (seen 55 at Fig. 2) will descend therefrom and make its exit from the next aperture below onto the higher portion of the inclined ball-surface of the shelf, communicating with said lower aperture. (See Fig. 4.) Thence the said ball or 60 balls, should it or they descend onto the last-named shelf toward its opposite end, would enter an aperture in the other pilaster substantially opposite to that at which it or they entered, from which the ball or balls would 65 descend one step to the next lower aperture, and thence out onto the highermost portion

of an opposite end of the next shelf, and so on, assuming, of course, the shelves to be in the proper relative position with the apertures in the pilasters to permit this operation.

70

At Fig. 4 the arrows on the drawings indicate the line of travel which the ball or balls must take in passing from the topmost to the lowermost shelf of the gang, and thence out from the rack into any suitable receptacle or 75 tray. In escaping from the rack, all the balls of course make their exit from the lowermost aperture in the right-hand pilaster, and onto a cushioned or cloth-covered inclined surface or roadway, *H*. From this point of discharge 80 they may descend immediately into any suitable tray, triangle, or other collecting device, which may be properly constructed to prevent the possibility of any ball falling on the floor; or, if deemed expedient, the lower portion 85 of the rack, in the vicinity of the discharge-surface *H*, may be provided with some suitable fender or guard-like device.

From what has already been explained, together with the drawings, it will be understood that in the use of my improved contrivance it is only necessary, after the receptacle for catching the balls shall have been placed in position on the floor or base of the rack, to bodily elevate the whole set of shelves 95 by turning the lifter device, when all the balls on any or all of the shelves will pass from the latter in opposite directions into the respective passage-ways forming communications between the adjacent ends of the successive 100 shelves, and, descending through the entire series, will all make their exit through the lowermost aperture of the right-hand pilaster, and thence into the tray or receptacle.

Of course, the arrangement as to the communicating passage-ways, and as to the alternate obliquity of the ball-supporting surfaces of the shelves, might be reversed and many changes or modifications might be made in the details of the structure shown, and without 105 materially changing its principles of construction and mode of operation, and hence without departing from the essence of my invention.

110 The lifter device is applied merely for convenience, and the gang of shelves might be conveniently operated by hand in the absence of any such device.

115 Of course, the lowermost part of the pool-rack, instead of being devised as shown, may be so modified in form and structure as to adapt it to the reception, or to the use in connection with it, of any sort of approved or improved combined tray and triangle or other ball-collecting contrivance that it may be desired to 120 use in connection with my invention. I do not therefore wish to limit my claim of invention either to the precise details of construction shown and described, nor to the precise construction of the pool-rack in any particulars which are not essential to the essence 125 or distinguishing feature of my invention,

115

120

125

130

which, it will be understood, consists in the use together of a set of lifting ball-shelves adapted to cause the balls to settle or roll toward opposite ends of the successive shelves 5 of suitable connecting passage-ways arranged adjacent to the ends of the shelves and communicating therewith only when the shelves are placed in the position in which it is designed they shall be emptied of their contents. 10 This end could of course be accomplished in substantially the same manner by having the obstruction to the exit of the balls from any one shelf located at the upper part of the ball-space, instead of at the lower part, by having 15 the shelves in such case lowered when desired to discharge their contents, instead of elevated, as shown in the present case.

Having now so fully explained the principle and operation of my invention as to en-

able those skilled in the art to practice the 20 same, what I claim as new, and desire to secure by Letters Patent, is—

In combination with a set or gang of bodily-movable shelves, the ball-supporting surfaces of which are inclined toward opposite ends of 25 the successive shelves, side passages or conduits forming communications between the adjacent ends of alternate pairs of shelves only when said shelves are set in a proper position designed to effect the automatic discharge of 30 their contents, substantially as hereinbefore set forth.

In testimony whereof I have hereunto set my hand this 2nd day of February, 1884.

H. W. COLLENDER.

In presence of—

JACOB FELBEL,
L. F. SILVOX.
